ATTORNEY.

UNITED STATES PATENT OFFICE.

GIUSTO BOGGIO, OF ROYALTON, ILLINOIS.

AUTOMATIC MINE DOOR.

Application filed September 4, 1925. Serial No. 54,455.

To all whom it may concern:

Be it known that I, Giusto Boggio, a subject of the King of Italy, residing at Royalton, in the county of Franklin and State of Illinois, have invented certain new and useful Improvements in Automatic Mine Doors, of which the following is a specification.

My invention relates to improvements in automatic mine doors, and has for its primary object a mine door which is equipped with an opening mechanism that is operated by the passage of the mine cars over the track.

A further object is to construct a mine door which is provided with an opening mechanism which can be operated from either side of the door and which will hold the door in open position until the car has passed entirely therethrough.

A still further object is to construct a mine door which will open regardless of whether the same has been prevented from entirely closing, as is sometimes caused where lumps of coal or mineral fall on the tracks and prevent the entire closing of the door.

The door may also be opened manually in the event that the opening mechanism becomes deranged through any cause whatever.

In the drawings:

Fig. 1 is a top plan view of my device showing the operating mechanism, and with parts thereof broken away;

Fig. 2 is a side elevation of Fig. 1;

Fig. 3 is a fragmental face view of a portion of the door and its operating mechanism; and

Fig. 4 is an enlarged vertical section taken on the line 4—4 of Fig. 1.

In carrying out my invention I employ ordinary tracks 5, which are mounted upon ties 6. Pivoted adjacent the tracks or rails 5 are levers 7. The opposite end of each of these levers is provided with a downwardly projecting portion 8, which enters a slot 9 preferably formed in one of the ties. This is for the purpose of guiding the lever and preventing it from shifting sidewise and out of contact with the wheel as it passes over the track.

The projection 8 is also provided with a slot 11, in which a tongue 12 formed integral with one end of the lever 13 extends. The opposite end of the lever 13 is also pivotally secured, but at a point on the opposite side of the door 14. This door will be more fully explained later.

Carried by the projection 8 is an arm 8^a to which a cable or chain 15 which passes over a sheave wheel 16 carried by the bracket 17 which is preferably secured to one of the ties. This wheel is mounted vertically, so that when the lever 7 is moved downward, a pull will be exerted on the chain or cable. From thence it passes forward and around the sheave 19, which is also located vertically. The opposite end of the chain is attached to the end 20 of a lever 22. The opposite end of this lever is pivotally attached to a rod 23, which extends into the hollow arm 24.

Within the arm 24 is located a coil spring 25 which has a cushioning effect on the rod 23 and which will also permit it to telescope in the arm 24 when necessary. The arm 24 is pivotally attached at 25^a to a curved end 26 of a bell crank lever. This lever is supported in a frame 27 which extends completely across the mine shaft. Carried by the lever is the door 14, which is thus pivotally hinged along its upper edge.

Carried by the frame 27 are doors 28, which are for the purpose of permitting miners to pass without operating the door 14. It is to be understood, of course, that the bell crank lever 26 has a similar crank on the opposite side of the frame, so that the door can be readily opened in either direction. Adjacent the pivoted ends of the levers 7 and located between the tracks is a V-shaped portion 29 which has its point located centrally of the track and diverges toward the rails. To both sides of this V-shaped portion are inclined portions 30, while on the outside of each of the rails are inclined inwardly-tapering portions 31. The purpose of these portions is that should the car be derailed through any cause whatever, it will not be necessary to stop the car to replace it on the rails, as these parts will automatically serve this purpose so that there will be no possibility of the wheels missing the lever 7 and opening the door.

The operation of my device is as follows:

When my car comes along the track, the wheels will necessarily strike one of the levers 7, depressing it. This depression of the lever will carry the projecting portion 8 downwardly and exert a pull on the chain 15. The pull on the chain 15 will cause the lever 22 to rock on its pivot point 32, thus pushing upward on the rod 23 and arm 24. This upward push will cause the end 26 of

the bell crank lever to turn and swing the door on a horizontal axis and open the same. By extending the levers 13 past the door, I am assured of a constant contact with the 5 levers and the consequent holding up of the lower edge of the door during the passage therethrough of the mine car, or even a train of cars, because at all times will one of the wheels of the car be in contact with 10 one of the levers holding the door open, and therefore all possibility of the door closing or even moving downwardly during the passage of a car is eliminated.

The spring 25 also serves the purpose of 15 allowing the end 26 of the bell crank lever to pass over center or past its lowest point. This is essential because if this feature were not present it would be impossible to operate the doors in opposite directions. Furthermore, should a lump of coal or other 20 mineral fall on the track and prevent the door from closing entirely, the end 26 will be past center and as soon as one of the levers 7 is contacted with, will operate the 25 door. This arrangement permits my door to be opened in either direction, regardless of the direction of travel of the mine car. The lever 7, however, is of sufficient length 30 so that should the door open towards the approaching car, which would be the case were the door blocked and prevented from closing entirely, sufficient space is provided to permit the door to swing outward to its 35 fullest extent before the car reaches the door, thus obviating the necessity of stopping the car to remove the obstruction from the track so that it can be swung in the opposite direction.

A leaf spring 18 is secured to one of the 40 ties 6. This is for the purpose of holding the free ends of the levers 7 and 13 up so that their weight will be removed from the cables, in this manner the swinging of the door 14 due to drafts is practically eliminated.

It is not necessary that my door swing 45 through an arc of ninety degrees. My intention is to have the door swing up only high enough to clear the cars and their load 50 so that when the door is fully opened, a horizontal position of the door will not be necessary, because the roof of the tunnel is sufficiently high to obviate this necessity. In other words, swinging the door through 55 an arc of between seventy and eighty degrees will be sufficient to accomplish my purpose. The amount of swing, however, will be governed by the height of the mine pas-

sage but at no time will the passage be so low as to compel the door to swing ninety 60 degrees from the perpendicular.

Having fully described my invention, what I claim is:—

1. An automatic mine door comprising a frame, a bell crank lever supported in said frame adjacent its top, a door secured to and depending from said bell crank lever, a lever pivotally mounted intermediate its ends located adjacent said frame, a connection between one end of said lever and said bell 65 crank lever, a flexible connection secured to the opposite end of said pivoted lever, and a lever mechanism secured to the opposite end of the flexible connection whereby said door is opened when the last mentioned lever mechanism is depressed.

2. An automatic mine door comprising a frame, a double bell crank lever mounted in said frame adjacent the top thereof, a door secured to and depending from said lever, a lever mechanism secured to each of said bell crank levers, a second lever mechanism located on each side of said frame and said door and adapted to be depressed by the passage of a mine car, and a connection between the last mentioned lever mechanism and the first mentioned lever mechanism whereby on the depression of the second mentioned lever mechanism the door is opened.

3. An automatic mine door comprising a frame, a double bell crank lever mounted in said frame adjacent the top thereof, a door secured to and depending from said lever, a lever mechanism secured to each of said bell crank levers, a second lever mechanism located on each side of said frame and said door, said lever mechanisms extending in opposite direction and so arranged that upon the passage of a mine car the contact with one of said lever mechanisms is not broken until after the other lever mechanism has been contacted with, and flexible connections between the last mentioned lever mechanism and the first mentioned mechanism whereby on depression of the second mentioned lever mechanism the door is opened and remains open until the car has passed a predetermined distance beyond the door.

4. The automatic mine door of claim 3 in which a portion of the lever mechanism connected to the bell crank lever is made telescopic whereby said door is permitted to swing in either direction.

In testimony whereof I have affixed my signature.

GIUSTO BOGGIO.
